N. Y., a corporation of Delaware

Application August 21, 1943, Serial No. 499,493

4 Claims. (Cl. 164—47)

The present invention relates to cutting apparatus for severing sheet material such as paper, e. g., photographic print paper.

A general object of the invention is the provision of an efficient cutting apparatus of simple and sturdy construction which may be employed rapidly and accurately to trim photographic print paper, and the like, or to sever pieces of accurate dimension from rolls thereof while permitting ease of manipulation and handling of the sheet material with effective elimination of danger of cutting the operator's fingers, and which requires a minimum of maintenance and repair.

A more specific object of the invention is to provide in such apparatus mechanism which provides for severing movement of a movable blade toward a fixed blade along a path substantially at right angles to the plane of the sheet-supporting bed by simple and efficient cam means.

Another object of the invention is the provision in such apparatus of blade-operating means including a manually depressible bar extending alongside of the bed structure to be readily accessible to and easily operable by the operator from a position most convenient to feed and arrangement of sheet material by the operator's hands.

A further object of the invention is to provide in such apparatus guard means which prevent the operator from putting his fingers in the cutting locale of the cutting blades while manipulating sheet material thereto, and which may additionally desirably limit thickness of fed material.

Still another object of the invention is the provision of transparent guard means on the approach side of the cutting blades which while eliminating danger to the operator's fingers permits visual inspection of the fed material in the vicinity of the cutting blades.

A still further object of the invention is the provision in such apparatus of adjustable sheet-guiding means to permit efficient guiding of fed material of differing widths and character.

Other objects of the invention will in part be obvious and will in part appear hereinafter.

The invention accordingly comprises the features of construction, combination of elements and arrangement of parts, which will be exemplified in the construction hereinafter set forth and the scope of the invention will be indicated in the claims.

For a fuller understanding of the nature and objects of the invention, reference should be had to the following detailed description taken in connection with the accompanying drawings, in which:

Fig. 1 is a top plan view, with parts broken away, of one embodiment of the present invention;

Fig. 2 is a longitudinal sectional view taken on line 2—2 of Fig. 1;

Fig. 3 is a transverse sectional view taken on line 3—3 of Fig. 1;

Fig. 4 is a transverse sectional view taken on line 4—4 of Fig. 2 showing blade operating mechanism; and

Fig. 5 is a horizontal sectional view taken on line 5—5 of Fig. 2, with the sheet supporting bed omitted and other parts broken away.

The present invention contemplates a sheet cutter apparatus including a bed structure for support of sheet material which may be in the form of a continuous roll to be fed thereacross or cut sheets to be fed therefrom to cutting mechanism. The cutting mechanism preferably comprises a fixed cutting blade and a cooperating movable cutting blade extending transversely of the bed structure in spaced apart relation when the movable blade is in its retracted position, with one, preferably the movable blade, located above the other. The movable blade is so mounted as to travel along a path substantially at right angles to the plane of the bed and preferably when in retracted position has its cutting edge at one end located nearer the cutting edge of the fixed blade than is the cutting edge at the other end to provide progressive transverse shearing when the movable blade is moved toward the fixed blade.

Means for operating the movable blade includes cam means which during rotary movement causes the movable blade to approach the fixed blade, and motive means to cause the cam means to rotate at least through a radial angle. Preferably the movable blade is spring-biased normally to hold it in retracted position with the cam means being operated in a manner to permit the biasing to return the movable blade to retracted position after it has been moved forward by the cam means. This may comprise a continuously rotating cam having a lobe which moves a blade-operating follower forward to a certain position and then passes it to release the follower and blade to be returned by the biasing means, but preferably comprises a cam which is rotated or oscillated back and forth through a radial angle so that as it is rotated in one direction it overcomes the biasing force of the biasing means and moves the blade forward and upon release is caused by the biasing means to rotate in the opposite direction to reset the mechanism.

The movable blade is preferably supported by structure capable of reciprocal action which carries a cam follower to be depressed by cam means when the latter is rotated through a radial angle by mechanism including lever means adapted to be pushed down by an operator's hand. The lever means preferably carries an elongated depressing bar mounted along the side of the bed to extend substantially at right angles to the severing plane, where it is most easily accessible to and operable by the operator's hands when he is in the best position for manipulation and feed of sheet material.

Guard means are preferably provided on the approach side of the cutting blades. This preferably comprises guard structure mounted on the bed structure which restrains approach of the operator's fingers to the cutting locale and may additionally be spaced from the surface of the bed structure a restricted distance to limit the thickness of fed material. This guard structure preferably is provided by a transversely extending bar supported above the top surface of the bed structure to provide a narrow slot for passage of sheet material of limited thickness and is preferably formed of transparent material, such as Lucite, to permit visual inspection near the cutting locale.

The bed structure is preferably provided with sheet-guiding means which may comprise a longitudinally extending fixed bar and a movable bar adjustably mounted in parallel relation thereto. Both bars are preferably undercut on their inside edges to provide with the bed surface a pair of opposed slots for guidance of the edges of a sheet. The opposed or outside edge of the movable bar is preferably provided with a straight flat surface disposed substantially normal to the bed surface to serve as a guide for cut sheets when the movable bar is reversed to face the flat edge surface toward the center of the bed. For this purpose the means employed to permit the movable bar to be moved transversely across the bed surface, and to lock it in any selected one of a number of positions for accommodating sheets of different widths, preferably permits complete detachment of the bar so that it may be reversed, end for end, to provide for selective use of either edge thereof.

These and other features of the apparatus of the present invention may become more apparent by reference to the accompanying drawings, in which like numerals refer to like parts throughout. A casing 10 provides a frame structure for support of various elements of the apparatus of the present invention. It includes end walls 11 and 12 and side walls 13 and 14. The casing 10 supports a bed plate 15 over which a strip of sheet material is to be fed or for support of cut sheets thereof. Within the casing 10 is supported a frame member or bracket 16 having a top plate section 17 and an end wall plate section 18 for the support of various elements. As shown in Figs. 2 and 4 the frame member 16 is preferably mounted on side walls 13 and 14. The top plate section 17 carries posts 19, 19 for support of the end edge of the bed plate 15. A pair of brackets 20, 20 are supported in spaced apart relation upon the plate section 17 and each includes a sleeve member 21 having a vertical bore extending therethrough. Arms 22, 22 support a transversely extending fixed blade 23 preferably having its cutting edge 24 disposed in the plane of the top surface of the bed 15.

Each sleeve member 21 reciprocatively carries

a plunger or rod 25, the upper end 26 of which extends above the sleeve 21 and is secured to a cross-bar 27. Each plunger 25 preferably has its upper end 26 provided with a flange 28 to form an abutment shoulder which rests upon the upper end of a coil spring 29 supported by the upper end of the sleeve member 21 to bias the cross-bar 27 to an upper retracted position.

A plate 30 is secured by a plurality of screws 31-31 to the cross-bar 27 and a movable cutting blade 32 is clamped therebetween. The blade 32 has its cutting edge 33 disposed at an angle to the cutting edge 24 of the fixed blade 23, that is, in the retracted position shown in Fig. 4, the cutting edge 33 at one end, for example, that nearest the left hand side of Fig. 4, or the back of the casing 10, is located nearer the cutting edge 24 than is the cutting edge 33 at the other end, so as to provide for progressive transverse shearing when the movable blade 32 is moved toward the fixed blade 23.

The rods 25, 25 reciprocatively mounted in the sleeves 21, 21 guide the movable blade 32 in its travel along a path substantially at right angles to the plane of the bed 15. This is accomplished by means of a cam follower mounted upon the lower ends of the rods or plungers 25, 25 and preferably comprises a transverse depressing bar 34 fixed to the lower ends of the rods 25, 25. The depressing bar 34 is preferably provided with a pair of spaced apart bearing plates 35, 35, each held by means of the biasing force of springs 29, 29 in contact with a lobe 36 of a rotatable cam 37. The cam 37 at the back of the structure is preferably pivotally supported by a stud 38 fixed to the end plate portion 18. A shaft 39 is rotatably supported in a bearing 40 mounted on the end wall 11 and a bearing 41 mounted on the wall portion 18 of the frame member 16.

The cam 37 nearest the front of the device or the casing wall 14 is fixed on the shaft 39 to be rotated therewith. The wall 14 is provided with a pair of vertically extending slots 42, 42 through each of which a lever arm 43 extends with the inner ends of the lever arms 43, 43 fixed on the shaft 39 to serve as means for rotating the front cam 37 through a radial angle. As shown in Fig. 4, cams 31, 37 are in the shape of bell cranks with the lower arm of each acting as a cam lobe 36, and with their upper arms 44, 44 connected together by a link 45 to cause the cams to be operated simultaneously.

The outwardly extending ends of the levers 43, 43 support therebetween a depressing bar 46 which extends along the side of the bed plate 15 substantially at right angles to the severing plane defined by the blades 23 and 32.

The brackets 20, 20 support a transversely extending guard bar 47 located on the approach side of the cutting blades 23 and 32. This guard means preferably comprises a bar of transparent material such as Lucite and is spaced a limited distance above the top surface of the bed plate 15 as shown in Fig. 2 to form a slot 48 through which sheet material is fed to the cutting blades.

Along the front edge of the bed plate 15 a sheet-guiding bar 49 is mounted in fixed position. This bar has its inside edge undercut at 50 to provide with the top surface of the bed plate 15 a slot for guidance of the edge of sheet material. This fixed guide bar 49 may also be provided at its outside edge with a groove, or may be undercut to provide with the top surface of the bed plate a groove, for the reception of the inwardly turned end of a slide indicator 51 as

shown in Fig. 3; the indicator being employable to guide margin severance between successive indicia-bearing areas on rolls of sheet material, such as successive pictures on photographic printing paper.

The bed plate 15 is also provided with a transversely movable guide bar 52 which is likewise undercut on the inside edge at 50 to provide an opposed slot for guidance of the other edge of sheet material. The bar 52 is mounted upon the bed plate 15 in any suitable manner so that it may be fixed in a plurality of positions to accommodate sheet material of differing widths. As shown in the drawings this may comprise a pair of slots 53, 53 in the bed plate 15, each receiving therethrough a bolt 54 having the threaded end thereof engaged in a nut 55 held in non-rotating fashion to the underside of the bed plate 15 by a pair of opposed channel members 56, 56 extending along the sides of the slot 53 to permit, when the bolts 54 are loosened, transverse sliding movement of the guide bar 52. This structure also permits complete free movement of the guide bar 52 by disengagement of the bolts 54, 54 from the nuts 55, 55 so that the guide bar 52 may be reversed, end for end, to present the back edge 51 of the guide bar toward the center of the bed plate 15 and, as seen in Figs. 1 and 3, the back edge 51 of the movable guide bar 52 is preferably formed as a straight flat surface disposed substantially normal to the top surface of the bed plate 15 so as to serve as a guide for cut sheets when this guide bar is reversed.

Preferably the end wall 11 of the casing 10 is slotted at 58 slidably to receive an arm 59, the projecting end of which supports a transversely extending rod 60 for support of a roll of sheet material. Adjustment of the spacing between the rod 60 and the end wall 11 is provided for accommodation of rolls of sheet material of different diameters. This is preferably accomplished by providing a slot 61 in that portion of the arm 59 within the casing 10 and mounting a bolt 62 therethrough to extend through a hole in the back side wall 13 for reception of the threaded end of a wing nut 63.

In operation when it is desired to employ the embodiment of the apparatus of the present invention shown in the drawings for separating different sections of a roll of sheet material, such as photographic prints which have been successively made on a roll of photographic printing paper, the latter is supported on the rod 60. The end of the roll of sheet material is carried up over the end of the bed plate 15 and after the movable guide bar 52 has been properly adjusted to accommodate that particular width of sheet material, the edges thereof are guided into opposed slots 50, 50. The sheet material is then fed to the cutting blades through the slot 48 beneath the transparent guard bar 47 to between the cutting blades 23 and 32. When so manipulated by the hands of the operator to the proper position for severances desired, as may be readily determined by visual inspection permitted by the guard bar 47, the depressing bar 46 is moved downwardly or depressed by either hand of the operator as he holds the sheet material in proper position with the other hand. Downward movement of the depressing bar 46 rotates the shaft 39 through a radial angle in a clockwise direction as viewed in Fig. 4. Shaft 39 carries with it the front cam 37 and the link 45 causes the back cam 37 simultaneously to rotate therewith. During such rotation through radial angles of the cams 37, 37,

the lobes 38, 38 thereof press down upon the depressing bar 34 to cause the rods 25, 25 to slide downwardly in the sleeves 24, 24. The rods 25, 25 carry with them the cross-bar 27 and the movable blade 32 so that the cutting edge 24 thereof progressively passes the cutting edge 24 of the fixed blade 23 thereby transversely severing the sheet material positioned therebetween. This action compresses the helical springs 29, 29 and upon release of the depressing bar 46 biasing force of the springs raise the movable blade 32 to the retracted position shown in Fig. 4. The lifting of the rods 25, 25 moves the depressing bar 34 upwardly thereby rotating the cams 37, 37 in the opposite direction to the positions shown in Fig. 4 and thereby resetting the mechanism for subsequent severing operation. It has been found in operation that the relative position of the manual operator or depressing bar to the feed of the paper and the severing plane or the plane of the blade action enables an operator to cut up to several thousand prints per hour.

It will thus be seen that the objects set forth above, among others, are efficiently attained by the apparatus of the present invention and since certain changes may be made in the above construction and different embodiments of the invention could be made without departing from the scope thereof, it is intended that all matter contained in the above description or shown in the accompanying drawings shall be interpreted as illustrative and not in a limiting sense.

It is also to be understood that the following claims are intended to cover all of the generic and specific features of the invention herein described, and all statements of the scope of the invention which, as a matter of language, might be said to fall therebetween.

Having described my invention, what I claim as new and desire to secure by Letters Patent is:

1. In a sheet cutter the combination with a bed for support of sheet material, a fixed cutting blade, a movable cutting blade and means to guide said movable cutting blade along a path substantially at right angles to the plane of said bed, of movable-blade-operating means comprising means biasing said movable blade to an upper retracted position and to lift it thereto, a depression bar connected to said movable blade, rotary cam means to ride upon said bar, lever means to rotate said cam means through a radial angle, and a depressing bar mounted on said lever means and extending along said bed substantially at right angles to said blade for manual operation of said movable blade during severing stroke thereof.

2. In a sheet cutter the combination with a bed for support of sheet material, a fixed cutting blade, a movable cutting blade and means to guide said movable cutting blade along a path substantially at right angles to the plane of said bed, of movable-blade-operating means comprising means biasing said movable blade to an upper retracted position and to lift it thereto, a depression bar connected to said movable blade, rotary cam means to ride upon said bar, lever means connected to said cam means to rotate the latter through a radial angle, and a depressing bar mounted on said lever means and extending along said bed substantially at right angles to said blade for manual operation of said movable blade during severing stroke thereof.

3. In a sheet cutter the combination comprising a transversely extending movable cutting

blade, a pair of spaced-apart fixed sleeves, a pair of rods with one fixed to one end of said blade and the other fixed to the other end of said blade and reciprocatively received in said sleeves, helical springs about said rods biasing said blade to an upper retracted position, a transversely extending depression bar connected between said rods, a pair of spaced-apart rotary cams each having a lobe riding on said bar, a link pivotally connected to both of said cams to cause simultaneous rotary movement thereof, a rotatable shaft to which one of said cams is fixed, lever means fixed to said shaft, and an elongated manual depressing bar mounted on said lever means and extending substantially at right angles to the severing plane defined by said blade.

4. In a sheet cutter, the combination com-

prising, a bed structure for support of sheet material, transversely extending cutting means, a fixed sheet-guiding bar extending along one side of said bed structure, a movable sheet-guiding bar adjustably mounted on said bed structure in spaced relation to and substantially parallel to said fixed bar, and bar mounting means to permit selective mounting of said movable bar at different distances from said fixed bar and reversal at will for selective employment of opposed edges thereof, said movable bar being undercut on one edge to provide with a bed surface an elongated slot for guiding continuous sheets and provided with a flat surface on the opposed edge to extend substantially at right angles to the plane of the bed surface for guidance of cut sheets.

RAY U. STRANDBERG.
